FRACTIONAL DISTILLATION

Earle W. Gard, Palos Verdes Estates, Calif., co-signer to Union Oil Company of California, Los Angeles, Calif., a corporation of California

Application May 21, 1932, Serial No. 612,782

9 Claims. (Cl. 196—189)

This invention relates to a process and apparatus for fractionating hydrocarbon oils, particularly petroleum.

This invention relates particularly to the withdrawal of side cuts from a main fractionating column and the exhausting and separate fractionation of the withdrawn cuts in an auxiliary rectifying column, to produce fractions of improved quality.

Heretofore, when a limited quantity of a hydrocarbon fraction having a definite boiling point range was desired, it has been common practice to withdraw from the proper intermediate point in a main fractionating column a portion of the descending reflux oil. This oil before removal from the main fractionating column is in approximate equilibrium with the vapors therein and therefore the withdrawn oil contains appreciable quantities of the high and low and intermediate boiling point fractions. It has been customary, therefore, in order to obtain a cut of limited boiling point range, to strip the above mentioned withdrawn reflux in an auxiliary exhausting column to remove the low boiling point components and yield therefrom a residual cut having the said desired boiling point range. The said removed low boiling point vapors have, in the past, either been returned from the exhausting column to a later stage of the main fractionating column, or run directly to the final condensing system or separately condensed. This has resulted, in the first case, in overloading the later stages of the main fractionating column when steam or other heating vapors are used in the exhausting section; in the second case has resulted in the contamination of the overhead condensate from the main column, with the heavy, high boiling ends which are carried over with the vapors from the auxiliary exhausting column; and in the third case has resulted in the necessity of separately refluxing this condensate with the attendant costly extra equipment and loss of heat.

The above enumerated disadvantages have been obviated by this invention.

In accordance with this invention a liquid fraction is withdrawn from an intermediate point in a main fractionating tower and without cooling, is stripped of its low boiling components in an auxiliary exhausting column, in countercurrent contact with a heated vapor such as hydrocarbon vapors or steam or by direct heating of the fraction. The stripped bottoms withdrawn from this exhausting column constitute the intermediate fraction of desirable high flask point

quality. The low boiling point vapors removed from the side cut in this process of exhaustion are fractionated to a desirable end point in countercurrent contact with reflux in an auxiliary fractionating column before being condensed. 5 The remaining fractions and the reflux formed in the auxiliary fractionating system are trapped and returned to an early stage in the main fractionating tower for continued treatment. The overhead vapors of the auxiliary fractionating column are withdrawn to a common final condenser or separate condenser.

The object of this invention is, accordingly, to produce from a side cut taken off from any point in a main fractionating tower, a bottom fraction which is exhausted to any desirable degree, and having a relatively high flash point. It is a further object of this invention to accomplish this operation in an efficient and economical manner.

Another object of this invention is to make it possible, by proper design and operation of the auxiliary rectifying column, to produce, from a side cut taken off from any point in the main rectifying column, an intermediate cut or fraction, the bottoms of which may be exhausted to any desired degree and to produce at the same time an overhead which may be fractionated to any specified end point.

Another object of this invention is to eliminate 30 the disadvantages of passing the unrefractionated vapors from the exhausting column directly to the condensing system.

Another object of the invention is to eliminate the sensitivity, and difficulty of control existing 35 heretofore in other fractionating systems, wherein large amounts of steam or other heated gases or vapors were introduced by such exhausting operations; and to avoid disturbing the operation, control, or fractionation in the main fractionat- 40 ing column.

Other objects of this invention will be apparent to those skilled in the art, from the following description.

This invention resides in a process and apparatus as described herein, designed to accomplish the stated object.

The drawing is referred to for a diagrammatic illustration of one embodiment of this invention.

The still 1 is of any suitable type for heating the oil to the proper temperature and at the desired pressure for introduction into the main fractionating tower 2. Said main fractionating tower is of any suitable type equipped with ver- 55

tically spaced fractionating members 3 and 4, which may be bubble plates or the equivalent thereof; hot oil feed line 5; residuum outlet 6; overhead vapor-line 7; reflux supply line 8; side 5 cut outlet line 10; divided side cut return or blank plate by-pass 11, with regulating valves 13 and 14; auxiliary fractionator reflux return line 15; vapor nozzle 16 in blank plate 17, which may be placed at any point within the height of 10 the column where it is desired to remove the side cut, as through outlet 10 and heating medium inlet 39. The side cut, instead of being taken from a special blank plate, such as said blank plate 17, may be taken directly from any 15 ordinary fractionating plate.

The auxiliary rectifying column 18 consists of exhausting section 19 and fractionating column 20 as a unit, separated by blank plate 21 with vapor nozzle 22 therein, and vertically 20 spaced fractionating elements 23 and 24. The fractionating elements may be of the bubble plate type or equivalent, as in the main fractionating tower. The connections to the auxiliary rectifying column are: side cut inlet 25, overhead vapor outlet 26, reflux inlet 27, residual fraction and reflux return outlet 28, heating agent inlet 29 and bottoms outlet 30. Numerals 31 and 32 designate partial and final condensers respectively. Pumps 33 and 34 return a portion of the condensate from the condensers 31 and 32 respectively to the fractionating columns for reflux. The excess light oil condensate, not used for reflux, flows to the light distillate storage through line 35. Line 36 is an additional point of introduction for reflux which may be supplied from any suitable external source. Heat exchanger 37 may be employed to supply heat to the side cut prior to its introduction into the exhausting column. Residuum may be run prior to storage, 40 through residuum cooler 38.

In operation, the heated oil is introduced into the main fractionating tower near the bottom through inlet 5. The vapors rise in the tower countercurrent to descending reflux oil, through 45 fractionating members 3 and 4 spaced vertically throughout the height of the tower. The said descending reflux in the tower is in approximate equilibrium with the ascending vapors, both of which vary in composition from top to bottom, 50 i. e., the descending reflux varies from a high ratio of light to heavy components at the top, to a high ratio of heavy to light components at the bottom. Blank plate 17 is accordingly placed in any position relative to the top and bottom of 55 the column where the side cut desired to be drawn off is of the proper composition. A number of such plates may be used, or the bubble plates may be so designed that any number of them may be used to draw off a number of different side cuts, each for separate treatment. The reflux so trapped on a blank plate such as 60 17 is withdrawn through line 10 and is divided, a portion thereof being introduced as a side cut into the auxiliary fractionating column through line 25, and the balance of the reflux being returned to the lower stages of the main fractionating column through by-pass 11. Reflux for the main fractionating tower is introduced at the 65 top through line 8 by pump 33, which pump draws upon the accumulated overhead condensate in the reflux drum supplied by the partial condenser 31. The bottoms are withdrawn 70 from the main fractionating tower through line 75 6 and either run directly through cooler 38 to the

residuum storage or through heat exchanger 37 prior to cooling.

The side cut is introduced through line 25 into the exhausting section 19 of the auxiliary rectifying column 18 at a point below the blank plate 5 21, where it flows downward through plates 24 in countercurrent contact with rising heated vapors and/or steam introduced through 29. The side cut is here stripped of its low boiling fractions. The thus exhausted or stripped liquid 10 is removed and run to storage through bottoms outlet 30. This bottoms constitutes the desired fraction of specified high boiling or high flash characteristics.

The vapors of the low boiling constituents removed from the side cut in the exhausting section 19 pass upward through vapor nozzle 22 in blank plate 21 into auxiliary fractionating column 20, and continue upward through fractionating sections 23 therein, in countercurrent contact with downward flowing reflux. Said reflux is introduced at the top through line 27 and is supplied either by means of pump 34 from a portion of the final overhead condensate from condenser 32 or from any other suitable source 25 through line 36. The balance of the final overhead condensate, not used for reflux, is delivered to storage through line 35.

The overhead vapors from the auxiliary fractionating tower are removed through vapor line 30 26, and are condensed—along with the other light vapors from the partial condenser—in the final condenser 32. The auxiliary fractionating column 20 is designed and operated in such a manner that the overhead issuing therefrom will meet the 35 specification, as to end point of the overhead condensate from the main fractionating tower, and can be mixed therewith in the final condenser without contaminating said condensate with high boiling point fractions. The reflux 40 formed in the auxiliary fractionation collects on the blank plate 21 and is removed through outlet 28 and returned through line 15 to an early stage in the main fractionating tower.

Steam, superheated steam, or any other medium 45 may be used to supply heat to the bottom of the exhausting section of the rectifying column, such as gases or vapors of any suitable nature; or heat may be applied externally, or through heating coils suitably placed; and/or heat may be 50 applied to the removed reflux oil prior to introduction into the auxiliary exhausting column by such means as heat interchanger 37 or other heating means, such as an externally fired tubular still similar to still 1. Heat may also be added 55 to the main rectifying tower as indicated at 39 or in the same manner as for the auxiliary rectifying column.

It will be understood that this invention is not 60 limited to the specific method and apparatus disclosed, since this disclosure is merely illustrative of one method and apparatus which may be employed, but includes any and all processes and apparatus within the scope of my invention, which I claim to be:

1. A process of fractionating hydrocarbons which comprises withdrawing a portion of the reflux from an intermediate point in a main fractionating column, withdrawing vapors from said fractionating column, passing the withdrawn reflux in countercurrent contact with heated vapors to remove low boiling point components therefrom, fractionating the thus removed low boiling point vapors in countercurrent contact with reflux oil in an auxiliary fractionating col- 75

umn out of contact with the vapors withdrawn from the main fractionating column, and returning the said last-mentioned reflux oil to the main fractionating column.

5. 2. A process of fractionating hydrocarbons which comprises withdrawing an intermediate reflux from a main fractionating column, withdrawing vapors from the main fractionating column, passing the said withdrawn reflux oil in 10 countercurrent contact with steam to remove low boiling components, thereby yielding an intermediate fraction of higher flash point, fractionating the said removed low boiling components in an auxiliary fractionating column out of contact 15 with the vapors withdrawn from the main fractionating column, and returning the reflux condensate from the said auxiliary fractionating column to the main fractionating column.

3. A process of fractionating hydrocarbons 20 which comprises withdrawing a portion of the reflux from an intermediate point in a main fractionating column, withdrawing vapors from the main fractionating column, passing the withdrawn reflux in countercurrent contact with heated vapors in an auxiliary exhausting column, to remove low boiling components, thereby yielding an intermediate fraction of higher flash point, fractionating the said removed low boiling point components in countercurrent contact with reflux 25 oil in an auxiliary fractionating column out of contact with the vapors withdrawn from the main fractionating column, thereby yielding an intermediate overhead fraction of specified end point, and returning the condensate from the 30 auxiliary fractionating column to the main fractionating column.

4. A process of fractionating hydrocarbons 35 which comprises withdrawing a portion of the reflux from an intermediate portion of a main fractionating column, withdrawing vapors from the main fractionating column, passing the withdrawn reflux in countercurrent contact with heated vapors in an auxiliary exhausting column to remove the low boiling point components therefrom, thereby yielding an intermediate fraction 40 of higher flash point, fractionating the said removed low boiling point components in countercurrent contact with reflux in an auxiliary fractionating column out of contact with the vapors 45 withdrawn from the main fractionating column to produce an intermediate low boiling point overhead fraction of specified end point, condensing the said overhead fraction, withdrawing the said 50 higher flash point fraction from the auxiliary exhausting column and returning the trapped reflux condensate from the auxiliary fractionating column to the main fractionating column.

5. A process of fractionating hydrocarbons 55 which comprises withdrawing reflux from an intermediate point in a main fractionating column, vaporizing and fractionating the withdrawn reflux oil in an auxiliary fractionating column and returning the reflux condensate from the auxiliary fractionating column to a lower stage

in the main fractionating column than the one from which reflux oil is withdrawn.

6. A process for fractionating hydrocarbons which comprises withdrawing a portion of the reflux oil from a main fractionating column, vaporizing the withdrawn reflux oil, fractionating the thus formed vapors out of contact with the said withdrawn reflux oil and returning reflux condensate from the last mentioned fractionating operation to a point in the main fractionating 10 column below that of the first mentioned withdrawal.

7. Apparatus for fractional distillation comprising in combination a vaporizer, a main fractionating column to condense and fractionate the 15 vapors from the vaporizer, an auxiliary vaporizer, means to withdraw a portion of the reflux condensate from said main fractionating column and to transfer said withdrawn reflux condensate to said auxiliary vaporizer, an auxiliary fractionating 20 column, means to pass vapors from said auxiliary vaporizer through said auxiliary fractionating column, means to withdraw overhead fractions from said auxiliary fractionating column, and means to transfer reflux condensate from said auxiliary 25 fractionating column to a point in the main fractionating column lower therein than the reflux condensate withdrawal means.

8. Apparatus for fractional distillation comprising in combination a vaporizer, a main fractionating column to condense and fractionate the 30 vapors from the vaporizer, an auxiliary vaporizer, means leading from an intermediate point of the main fractionating column to withdraw a portion 35 of the intermediate reflux condensate therefrom and to transfer said withdrawn reflux condensate to said auxiliary vaporizer, an auxiliary fractionating column, means to pass vapors from said auxiliary vaporizer through said auxiliary fractionating column, means to withdraw overhead 40 fractions from said auxiliary fractionating column, means to transfer reflux condensate from said auxiliary fractionating column to a point in the main fractionating column lower therein than the reflux condensate withdrawal means, and 45 means to withdraw unvaporized reflux condensate from said auxiliary vaporizer.

9. Apparatus for fractional distillation comprising in combination a vaporizer, a main fractionating column to condense and fractionate the 50 vapors from the vaporizer, an auxiliary exhausting column, means to withdraw a portion of the reflux condensate from said main fractionating column and transfer said reflux condensate to said 55 exhausting column, an auxiliary fractionating column and means to transfer vapors from said auxiliary exhausting column to said auxiliary fractionating column, means to conduct the auxiliary reflux condensate from said auxiliary fractionating column to a point in the main fractionating column lower therein than the reflux condensate withdrawal means and means to withdraw exhausted bottoms from the exhausting column and fractionated vapors from the auxiliary fractionating and main fractionating columns. 60 65

EARLE W. GARD.
